CLAIM

The ornamental design for a switch door, as shown and described.

DESCRIPTION

FIG. 1 A perspective view of the switch door of the present invention;

FIG. 2 A bottom view;

FIG. 3 A front elevational view; and,

FIG. 4 A right side elevational view.

The side not shown is a mirror image of the side that is shown in FIG. 4. The appearance of the rear of the door forms no part of the claimed design.
